CLAIM

The ornamental design for locking jumper cables with holder, as shown and described.

DESCRIPTION

FIG. 1 is a front and upper right perspective view of a combined set of four locking jumper cables and supporting holder showing my new design with one cable clamp detached from the holder;

FIG. 2 is a front elevational view of a combined set of four locking jumper cable and supporting holder showing my new design;

FIG. 3 is a rear elevational view thereof;

FIG. 4 is a left side elevational view thereof shown in the inverted position;

FIG. 5 is a right side elevational view thereof shown in the inverted position;

FIG. 6 is a top plan view thereof; and,

FIG. 7 is a bottom view thereof.

FIG. 1

FIG. 2

FIG. 6

FIG. 3

FIG. 7

FIG. 4
